MOBILE FIGURE

Filed Aug. 2, 1923

FIG. 1.

FIG. 2.

FIG. 3.

INVENTOR
GEORGIA W. PAGE

BY
Seward Davis
ATTORNEY

UNITED STATES PATENT OFFICE.

GEORGIA W. PAGE, OF NEW YORK, N. Y.

MOBILE FIGURE.

Application filed August 2, 1923. Serial No. 655,188.

To all whom it may concern:

Be it known that I, GEORGIA W. PAGE, a citizen of the United States, residing in the borough of Manhattan, in the city, county, 5 and State of New York, have invented certain new and useful Improvements in Mobile Figures, of which the following is a specification.

This invention relates to a device adapted 10 for use as a decoy, and also usable as a toy. It has for its objects the provision of a figure representing an animate object, so fashioned and mounted as to be readily movable, responsively to the elements. Fur- 15 ther objects are to construct said device strongly and cheaply, so that while it will not be readily injured, for example, by being hit by bird shot when shot over as a decoy, yet the cost of its replacement is 20 trifling.

With the foregoing objects in view and also certain objects of structural utility and advantage as hereinafter pointed out, my invention consists in the representation, for 25 example, of a bird or other creature, of light material; in the mounting of such figure in a hollow base by means consisting in part of a pivotally suspended counter-weight, so that the figure will rock as the 30 counter-weight oscillates; in the proportioning of the counterweight to the weight an area of the figure so that a light breeze will suffice to set the figure in motion, which motion will continue for an interval before 35 the movable parts come to rest; in the provision of a rigid support for said base adapted to be stuck in the soil and to maintain the device firmly upright, so that it will not be readily overturned, as by the flow 40 of ripples on the strand when stuck in the sand, and finally to provide such a base as will conceal but not interfere with the freely swinging pendant weight, and which base lends itself readily to concealment, as 45 by being banked with sand or camouflaged.

In the accompanying drawings forming part of this specification is illustrated the preferred embodiment of my invention. In these drawings, Figure 1 is a view in vertical elevation of the device, underlying parts being shown in outline. Figure 2 is a vertical sectional view on the line 2—2 of Figure 1 looking in the direction indicated by the arrow. Figure 3 is a cross-sectional view on the line 3—3 of Figure 1, looking in the direction indicated by the arrow.

The like or same parts are indicated by like numerals in these figures, in which 1 is a silhouette of a conventionalized bird, mounted upon the twisted strip of sheet metal 2, formed with lugs 3 serving as gudgeons journaled in holes 4 in the casing 5. The strip 2 is slotted to receive the disc 6, which is preferably notched at 7 to receive the extremity 8 of the disc in such notch and is oppositely notched at 9 to receive the tang 10 formed by extensions of the sides of the slot, and serves to secure the disc in place when bent back into the plane of the strip 2. The casing 5 is formed 60 as an oblong rectangle from a single piece of sheet metal bent, lapped and joined as at 11. Attached to the casing is the supporting member 12, so formed as to be thrust easily into the ground and strengthened by stiffening flanges 13 which are affixed to the casing, as by solder.

In the device as illustrated, the figure 1 is a stamping of sheet metal, slotted to receive the bent end of the strip 2, which is then 65 bent over to secure the figure in place. This construction affords lightness of the moving parts, and by the knife-edge support by which the pendulum is suspended, renders the decoy sensitive to light breezes, as by the 70 air currents caused by breaking waves, when the decoy is set up on the beach, so that the 75 figure comes slowly to rest.

The casing is preferably made open at the bottom for drainage, as water would be held 80 therein if a bottom were provided and the weight would be impeded.

While the mobile figure itself is shown as a silhouette, this is not intended as a limitation thereto since such figure may be made 85 in fuller representation of the bird or the like to be decoyed, without departing from my invention, the spirit thereof being fulfilled if the figure is so light as to be readily mobile responsive to light winds. For example, the figure may be hollow by molding 90 from celluloid, or may be of solid cork or fabricated from any suitably light and preferably waterproof material. Obviously, when intended as a plaything, the representation need not be of a game bird, but may 95 be of any animate object so proportioned as to be operably responsive to the elements, either wind or wave, by which is to be understood that the device may be stuck up 100 in the sand where the ripples may partially submerge it, and cause it to function if the 105 110

bottom of the casing is slightly above the ground, so that water may flow thereunder and set the pendulum in motion and thereby move the figure.

5 Having thus described my invention, I claim:

1. A mobile figure representing an animate object mounted rigidly upon a support consisting of a metallic strip, a casing laterally enclosing said strip and open at the top and bottom, pivots on said strip consisting of extensions thereof seating in openings in said casing, the weight of the strip below the pivots being sufficiently greater than the 15 weight of the figure and its support above the pivots to tend to maintain the figure upright while permitting same to oscillate freely, and means for maintaining the casing in vertical position consisting of a downward 20 extension thereof adapted to be thrust in the ground.

2. A mobile decoy comprising a metallic silhouette, a metallic strip supporting said figure and twisted therebelow at right 25 angles to itself, lugs upon said strip journaled in a casing, an extension of said strip

below said lugs, a disc attached to said strip and adapted to counterpoise said silhouette and said casing, the said casing consisting of a metal sheet bent to surround and enclose 30 the disc and strip, excepting the upper end thereof, and having a projection adapted to be stuck in the ground.

3. A mobile decoy comprising a metallic silhouette, a metallic strip supporting said figure and twisted therebelow at right angles to itself, lugs upon said strip journaled in a casing, a slotted extension of said strip 35 below said lugs, a disc mounted in said slot and adapted to counterpoise said silhouette, the diameter of said disc exceeding the height of the slot, a tongue integral with said strip and extending downwardly into said slot and adapted to seat in a recess in said disc and to hold said disc within the 40 slot and at right angles to said strip when a recess in the opposite side of the disc receives the lower edge of the slot; and the said casing, which said casing surrounds and encloses the disc and strip, excepting the 45 upper end thereof.

GEORGIA W. PAGE,
